UNITED STATES PATENT OFFICE.

ELLIS S. LINCOLN, OF MANSFIELD, OHIO, ASSIGNOR TO THE OHIO BRASS COMPANY, OF MANSFIELD, OHIO, A CORPORATION OF NEW JERSEY.

CURRENT-COLLECTOR SUPPORT.

Application filed September 30, 1921. Serial No. 504,430.

To all whom it may concern:

Be it known that I, ELLIS S. LINCOLN, a citizen of Sweden, residing at Mansfield, in the county of Richland and State of Ohio, have invented certain new and useful Improvements in Current-Collector Supports, of which the following is a specification.

My device relates to trolley poles for use in supporting current collecting devices upon cars or busses and while it may be used in the ordinary track system of transportation, it is particularly adapted to the trackless trolley system of transportation.

My invention has for its object a pole or structure to be mounted at one end on a bus in any of the usual well known ways, and upwardly spring pressed, and arranged to carry current collecting means at the other end and in the case of trackless trolley operation where the cars are insulated from the ground by rubber tires and it is necessary to use two overhead conductors, a positive and a negative, the collecting devices are so mounted as to permit their separation to be varied to meet changes in the spacing of the conductors and to meet variations in relative vertical height of the conductors.

My invention also permits the bus to operate many feet to either side of the conductors under which condition the trolley pole must make a considerable angle with the bus and conductors and permit the current collectors to maintain their relation with each conductor.

In the accompanying drawings—

Fig. 1 shows a top plan view of my invention with current collectors mounted thereon and insulated therefrom.

Fig. 2 shows a side view in elevation.

Fig. 3 shows a top plan view enlarged of a portion of the head member shown in Figs. 1 and 2.

Fig. 4 is a section of Fig. 3 on line 4—4.

Fig. 5 is a section of Fig. 3 on line 5—5.

In the form shown and described a portion of a pole 1 is shown, it being understood that the length may be anything desired. To the end of the pole is secured a head H mounted to swivel about the axis of the pole 1 to a limited degree and to carry the arms 2 which may be of metal or insulating material such as wood or bamboo. When the arms are of metal I insert between the fork members F and the arms 2—2 an insulating member 3. The arms are so mounted

on the head H that their angular spacing may be varied as required under operating conditions. The head H is provided with a sleeve 4 secured to the shaft by a key h. One end of the sleeve is provided with a collar 5 having two slots 6—6 therein. The opposite end of the collar is provided with a screw thread and collar 7 engaging therewith and maintains the body 8 in position on the sleeve. The body 8 is mounted to rotate or pivot to a limited degree upon the sleeve 4 and the rotation is limited by projecting lugs 9—9 engaging the end walls 10 of the slots 6—6.

To the body 8 are pivotally mounted a pair of clevis members 11 each provided with a socket 12 to receive the arm 2. Each clevis member is mounted on the body 8 by means of the anti-friction members 13—13 and the bolt and nut 14. The clevis members 11 are limited as to the amount of swivel by means of the set screws 15 engaging adjacent portions of the body.

The pivotal joint secured by the head H permits easy adjustment of the collectors F due to the swinging of the bust or the variable height of the conductors or both, and the pivotal joint secured by the clevis 11 permits the transverse distance between the collectors to vary due to any variation in the spacing of the conductors or the operation of the bus to either side of the center line of the conductors.

If not desired to have the two arms 2—2 secured to one pole member 1 but to operate with each collector and arm attached to its own pole 1, it is quite evident this is a simple change which can be made by making the head H with a single arm connection. With the collector insulated from the arm it is necessary to connect to the collector a cable which conducts the current to the bus.

Having shown and described my invention, I claim—

1. The combination with a plurality of conductors of a support comprising a main member, a head swivelly mounted thereon to rotate about the axis of the main member, a plurality of arms pivotally mounted upon the head to move in a common plane and forming angles with said axis and means for the attachment of current collecting means to each of the arms to engage the conductors.

2. The combination with a plurality of

- conductors of a support comprising a main member, a head swivelly mounted thereon to rotate about the axis of the main member, means to limit the amount of rotation, a plurality of arms pivotally mounted upon the head to move in a common plane and forming angles with said axis and means for the attachment of current collecting means to each of the arms to engage the conductors.
10. 3. The combination with a plurality of conductors of a support comprising a main member, a head swivelly mounted thereon to rotate about the axis of the main member, a plurality of arms pivotally and independently mounted upon the head to move in a common plane and forming angles with said axis and means for attachment of current collecting means to each arm to engage the conductors.
15. 4. The combination with a plurality of conductors of a support comprising a main member, a head swivelly mounted thereon to rotate about the axis of the main member, a plurality of arms mounted upon the head and means for attachment of current collecting means to each arm to engage the conductors.
20. 5. A support for current collecting devices comprising a member, a pair of arms operating to change their angular spread independently of each other, and means interposed between the arms and the member to secure the arms to the member to pivot about the axis of the member as a center.
25. 6. A support for current collecting devices comprising a member, a pair of arms operating to change their angular spread independently of each other, means interposed between the arms and spring-pressed member to secure the arms to the member in a rotative relation thereto about the axis of the member and means to limit the amount of said rotation.
30. 7. A support for current collecting devices comprising a main member, a plurality of arms, means connecting the arms to the main member in pivotal relation thereto about the axis of the main member as a center of rotation and means limiting the amount of rotation of the connecting means.
35. 8. A support for current collecting devices comprising a main member, projecting means to receive a current collecting device and means interposed between the main member and the projecting means and mounted on the main member in pivotal relation thereto about the longitudinal axis of the main member as a center.
40. 9. A support for current collecting devices comprising a main member, projecting means to receive a current collecting device, means interposed between the main member and the projecting means and mounted on the main member in pivotal relation thereto and means to limit the amount of pivotal
- rotation about the longitudinal axis of the main member as a center.
10. A support for current collecting devices comprising a main member and auxiliary means to which current collecting means is attached and connecting means interposed between the main member and the auxiliary means to rotatably connect the parts, the connecting means comprising a sleeve secured to the main member and having its axis extending in the same direction as the axis of the main member and a member surrounding the sleeve in rotatable relation thereto.
15. A support for current collecting devices comprising a main member and auxiliary means to which current collecting means is attached and connecting means interposed between the main member and the auxiliary means to rotatably connect the parts, the connecting means comprising a sleeve secured to the main member and a member surrounding the sleeve in rotatable relation thereto about the longitudinal axis of the main member as a center and means interposed between the sleeve and the member mounted on the sleeve to limit the rotation of the parts.
20. 12. A support for current collecting devices comprising a main member and auxiliary means to which current collecting means is attached and connecting means interposed between the main member and the auxiliary means to rotatably connect the parts, the connecting means comprising a sleeve secured to the main member and a member surrounding the sleeve in rotatable relation thereto and means to limit the rotation of the rotatable member about the longitudinal axis of the main member as a center.
25. 13. An article of manufacture comprising a sleeve adapted to be secured to a trolley pole in detachable relation thereto and having their longitudinal axes extending in the same direction, a rotatable member mounted on the sleeve, means on the sleeve to maintain the parts in operative relation and means mounted on the rotatable member in pivotal relation thereto to receive a current contacting member in fixed relation to said means.
30. 14. An article of manufacture comprising a sleeve adapted to be secured to a trolley-pole in detachable relation thereto and having their longitudinal axes extending in the same direction, a rotatable member mounted on the sleeve, means on the sleeve to maintain the parts in operative relation, means mounted on the rotatable member in pivotal relation thereto to receive a current collecting member in fixed relation to said means and means coacting with the sleeve and rotatable member to limit their relative rotation.
35. 15. The combination with trolley pole of

- one or more independently movable arms mounted on the arm in rotatable relation thereto about the axis of the arm as a center of rotation and each arm carrying a 5 swivelly mounted current collector all for the purpose and as described.
16. A support for current collecting device comprising a main member, projecting means rotatably mounted on the main member 10 to receive a current collecting device, and means to limit the amount of rotation about the longitudinal axis of the main member as a center.
17. A supporting arm as described and 15 two auxiliary arms movably mounted thereon to pivot toward or away from each other in the same plane as described.
18. A supporting means and two auxiliary means movably mounted thereon to 20 pivot toward or away from each other as described.
19. A supporting arm and two auxiliary members pivotally mounted thereon and each forming an angle with the axis of the 25 arm as described and operating to pivot toward or away from each other to change their angular relation.
20. The combination with a supporting arm of two or more movable arms mounted 30 on the supporting arm to receive current collecting devices and forming a changeable angle at diversion with each other.
21. A support for current collecting means comprising a supporting member, 35 means movably mounted thereon to receive current collecting means and pivot in a horizontal plane when the movable member rests in a horizontal plane.
22. A support for current collecting means 40 comprising in combination a supporting member, means pivotally mounted thereon to receive current collecting means and move in a plane, about its pivot point, common with the axis of the movable member.
23. A support for current collecting devices comprising a supporting member, a pair of arms operating to change their angular spread, mounted on said member to support the collecting devices. 45
24. A support for current collecting devices comprising a supporting member, a pair of arms swivelly mounted on the member to move in a common plane and forming angles with the axis of the member. 50
25. A current collecting device comprising a supporting arm, a pair of auxiliary arms and a current collector secured to each arm, the auxiliary arms pivotally mounted on the supporting arm to permit the collectors to move toward or away from each other about 55 the pivotal point as the center of movement.
26. A support for current collecting devices comprising a main member, a pair of arms provided with current collecting means, means connecting the arms to the main member comprising means to permit the arms to move transversely of the main member and means permitting the arms to move in a direction at right angles to the above direction of movement, the last said means compelling one arm to move simultaneously with and in an opposite direction to the other arm. 65
27. The combination with a trolley pole, of a pair of contact-carrying arms pivotally 70 supported thereby for movement transversely on the pole. 75

In testimony whereof I affix my signature.

ELLIS S. LINCOLN.
